UNITED STATES PATENT OFFICE

126,849

DESIGN FOR A VIBRATOR

James J. Flatley, Hollywood, Calif.

Application September 7, 1940, Serial No. 94,875

Term of patent 7 years

To all whom it may concern:

Be it known that I, James J. Flatley, a citizen of the United States, residing in the city of Hollywood, county of Los Angeles, and States of California, have invented a new, original, and ornamental Design for a Vibrator, of which the following is a specification, reference being had to the accompanying drawing forming part thereof.

Fig. 1 is a perspective view of a vibrator showing my new design. Fig. 2 is a side elevational view thereof.

I claim:

The ornamental design for a vibrator, substantially as shown.

JAMES J. FLATLEY.
